UNITED STATES PATENT OFFICE.

EDMOND DELILLE, OF LYON, FRANCE.

ELECTRIC HEATER.

1,373,117.

Specification of Letters Patent. Patented Mar. 29, 1921.

Application filed May 12, 1919. Serial No. 296,630.

To all whom it may concern:

Be it known that I, EDMOND DELILLE, of Lyon, France, manufacturer of electrical apparatus, a citizen of the French Republic; have invented certain new and useful Improvements in Electric Heaters, of which the following is a specification.

Electric heating is realized by means of a "resistance" formed of a determined length of wire rolled or arranged in any other manner and brought to a certain temperature by the electric current passing through it. This resistance has generally been placed on or in asbestos, refractory earth or other incombustible matter. The heat developed is utilized, either directly as in radiators, or indirectly by the use of parts made of metal which is a good conductor of the heat, said parts heated by conductibility. In the latter case the resistance or its incombustible support is in direct contact with the heating members: the resistance is therefore imprisoned in a space void of air. The result is that the resistance has first to transmit calories to an athermanous body, the volume of which takes a comparatively long time to attain the degree of desired normal temperature.

The device which forms the object of the invention is essentially characterized by the fact that the resistance is insulated from any contact with a heating member and that it is suspended inside a closed inclosure without communication with the atmosphere. This inclosure assumes various forms which vary with the apparatus and their applications, but it is always wholly or in part composed of metals which are conductors of heat. The temperature to which the resistance is brought at the passage of the electric current is utilized, in this device, on the one hand to heat the air contained in the closed inclosure, on the other hand to heat by its radiations the inner surfaces of the inclosure which are the most directly exposed to said radiations.

The annexed drawing illustrates by way of example the application of the invention to the heating of a smoothing-iron. Figure 1 is a longitudinal section: Fig. 2 is a plan view as seen from below of the resistance and its support removed from the iron.

The iron is composed of two half-shells a and v . The lower half v is hollowed out as at h l , Fig. 1 and provided with bosses b^1 b^2 for the purpose hereinafter described.

The flange c surrounding the lower half-shell v is provided with an interior groove j , into which is fitted a plate d seen in detail in Fig. 2. This plate is formed of asbestos, cardboard, or of any other insulating materials sufficiently rigid and capable of forming a joint. The upper shell a is insulated from the flange of the lower shell v by the plate d and it rests on the latter by means of a rib r of small surface.

By this construction, cavities h l are left in the iron beneath the plate d and cavities k above the plate.

The resistance g is wound spirally around a metal armature b , preferably of pure nickel or a suitable alloy, the armature being insulated by a suitably luted braiding of asbestos, in order to prevent it disaggregating. The spirals of the resistance are of such diameter that the air can circulate freely between the support e and between each of them: said spirals are, moreover, nearer to each other at the point than at the tail of the armature, for the purpose of heating more the forepart of the iron, which has a tendency to cool in the action of ironing.

The heating element thus formed is longitudinally inclined in relation to the plane of the base, in order to cause movement of the air contained in the cavity and obtain a good output owing to convection. This heating element is secured underneath the plate d by means of threads f of asbestos passing through the plate. At the point of the armature is arranged a cross-piece of refractory material m to which is secured the fixing thread f . These asbestos threads f are then covered with a cement in order to avoid disaggregation and also in order to insure the securing of the heating element to the plate. The ends of the resistance g are nipped in the bent part of contact plates of copper p and n respectively, which pass through the plate and are firmly held thereto by suitably folding them as shown in Fig. 1.

The body v of the iron, the plate d , and the cover shell a are, for example, connected by means of screws t or of pins, separated from the handle support u by insulating disks. The cover shell a is formed with a raised portion a^1 on which are fixed two contact pins i , the base of which projects inside the cover. The said pins are arranged opposite the plates p and n in order

to press on the latter when the cover shell α is put in place.

It is understood that at the moment when the current leads are placed on the pins i the electric current runs over the resistance g and makes it red-hot; the air inclosed between the two shells immediately is heated and quickly attains a very high temperature: on the other hand, the direct radiations emitted by said resistance heat the bosses and the inner wall of the shell v . The latter is consequently heated under the working of both these emissions and attains a relatively high temperature which is kept constant so long as the current runs through the resistance.

As soon as the electric circuit is broken this temperature is lowered, since the source of heat is cut off, but the body v only cools very slowly, owing to the air-tightness of the two shells, which does not allow the outer air to penetrate into the inner chamber and enables the inclosed air to remain hot for a relatively long time.

By varying the thickness of the heating walls, the length and diameter of the resistance wire, the temperature which the apparatus is to attain will be easily determined.

According to the various applications of this invention, the inclosure will receive various shapes suitable for the use of the respective apparatus. The resistance will also be of the desired shape and of dimensions calculated in proportion to those of the closed chamber in which it will be placed.

What I claim as my invention and desire to secure by Letters Patent of the United States is:—

1. In an electric heater, the combination of a member to be heated having a chamber therein; an electric heating element located in said chamber, the latter being of such size relative to the heating element as to inclose a predetermined volume of air surrounding the heating element on all sides; an incombustible support for said resistance; and means for supporting said support in said chamber, said chamber being constituted by two hollow members, hermetically sealed at their junction and said last named means being located at said junction.

2. An electric sad iron comprising a base portion; an upper portion superposed on the base portion, said base and upper portions being hollow and constituting an air chamber when assembled in superposed relation; a plate-like, resistance carrying element in-

terposed between the base portion and the upper portion; and means carried by the base and upper portions for holding said plate in said air chamber between the upper and lower portions.

3. An electric sad iron comprising a base portion; an upper portion superposed on the base portion, said base and upper portions being hollow and constituting an air chamber when assembled in superposed relation; a plate-like, incombustible resistance carrying element interposed between the base portion and the upper portion; and means carried by the base and upper portions for holding said plate in said air chamber between the upper and lower portions.

4. An electric sad iron comprising a base portion; an upper portion superposed on the base portion, said base and upper portions being hollow and constituting an air chamber when assembled in superposed relation; a plate-like, resistance carrying element interposed between the base portion and the upper portion; and a ledge carried circumferentially on said base portion for carrying said plate.

5. An electric iron comprising three distinct and separate units, to wit, a base, a cover, and a plate-like, resistance carrier, the latter being interposed between the base and the cover; screws passing through the cover and threaded into the base, said units being structurally separate before said screws are set and tightened; plug-contact terminals carried by the cover; and means, carried by the plate-like resistance carrying unit and connected to the resistance, adapted to make contacting engagement with parts of said plug-contact terminals of the cover unit when said units are assembled and secured in place by said screws.

6. In an electric iron, the combination of a member to be heated comprising an upper member and a base member spaced to provide an air chamber between them; a plate element interposed between said portions; and a resistance element suspended from said plate; said resistance element sloping downwardly from the heel of the iron toward the toe thereof to cause the heating effect of the resistance on the base portion to be greater at the forward part of the iron.

In witness whereof I have signed this specification in the presence of two witnesses.

EDMOND DELILLE.
